UNITED STATES PATENT OFFICE

DENNIS PARKS, OF ST. LOUIS, MISSOURI.

MOLDER'S FLASK.

No. 880,396.

Specification of Letters Patent.

Patented Feb. 25, 1908.

Application filed August 15, 1907. Serial No. 388,588.

To all whom it may concern:

Be it known that I, DENNIS PARKS, a citizen of the United States, residing in the city of St. Louis and State of Missouri, have invented new and useful Improvements in Molders' Flasks, of which the following is a specification.

This invention relates to the art of molding, and has for its object improvements in the construction of the flask, or receptacle, used by the molder for containing in molded form the sand which has been packed about a pattern.

The invention aims to provide a flask, or flask-member, in which provision is made for accommodating patterns of varying heights and configurations, and for insuring the firm retention of the molded sand in the flask after the pattern has been withdrawn.

20 The invention is directed, more particularly, to the cope, or upper member of the flask, which, after the sand has been packed therein about the pattern must be turned and the pattern withdrawn, and then turned again and placed in position on the drag, or lower member of the flask. Great difficulty has been experienced in providing means for securely holding the sand in the cope so that it will not fall out when the cope is turned

30 over, and this difficulty is increased when the nature of the pattern requires a thin layer of sand, or thin, or narrow, projecting bodies of sand to be supported, these parts of the molded sand frequently falling out,

35 when the cope is reversed, upon the molded sand in the drag, and necessitating the re-packing of both members of the flask. To overcome this difficulty, some foundries, whose work is restricted to special articles,

40 such as bath-tubs, or the like, have adopted the expedient of providing a special construction of cope, in which provision is made for adequately supporting the sand; such copes, however, are of no use in molding any

45 other article. Aside from these special constructions, the well-nigh universal custom is to secure a number of wooden or iron bars in the cope, to cut away or cast these bars on one side to conform, in a general way, to the shape of the pattern, and then, in the

50 case of wooden bars, to drive a large number of nails part way in each bar, the projecting heads of the nails being relied on to support the sand. These nails, however,

55 expanding under the intense heat of the molten metal, enlarge and burn the holes in

the wood to such an extent that on cooling they frequently drop out, and more nails must be driven in the bars. Furthermore, the nails falling out get mixed in with the sand, and must be removed by careful sifting of the latter. The use of specially constructed bars, such as metal bars provided throughout their length with holes, and having in their lower edges dove-tailed grooves, adapting them to support the sand, has been suggested, to avoid the use of nails. Such constructions, if practicable at all, are expensive, as it is manifest the bars in each cope must be shaped to conform to the particular pattern to be molded, and that a cope provided with such specially-shaped bars would be useful only in connection with the special pattern for which it was constructed. And even where a vertical adjustment of the bars in the cope is provided for, which has been suggested, the range of use of such copes is only very slightly extended, and is still necessarily limited to molding articles having a comparatively flat surface. In other words, as the sand-supports (such as the heads of nails) must approach to within about one-fourth inch of the molded surface in order to support the sand, it is manifest that a straight bar cannot be used with a pattern having either a curved or an irregular surface, and that bars shaped to conform to a particular surface, cannot be used with a pattern having a surface of another shape or configuration. I believe the above represents, in a general way, the present state of knowledge as to this phase of the art of molding, and, so far as I am aware, no one has ever heretofore produced a flask member with provision for adjustably mounting a series of sand-supports, or anchors, therein in such manner as to render the same capable of use with any shape or configuration of pattern whatsoever within the limits of the capacity of the flask, and so that the same flask member, or cope, may be used with different patterns, in each case requiring merely an adjustment of the sand-supports to conform to the particular shape of the pattern to be molded.

Heretofore, the services of a skilled artisan, or, at least, a thoroughly experienced workman, were required to prepare a cope for use with a pattern of an irregular configuration. My invention, on the other hand, provides such a simple means of securing the

desired adjusted position of the sand-anchors, or supports, that a mere novice, after having the device explained to him, can readily prepare a cope for use with any given pattern, and in a fraction of the time required under the present system of cutting away the wooden bars to the required shape, and then driving nails therein.

Having thus outlined, in a general way, the purposes and advantages of my invention, I will proceed to describe the same, and the manner of its use, referring to the accompanying drawings, in which:

Figure 1 is a cross-sectional view through a cope provided with my improvements, one of the bars for holding the sand-supporting devices being shown partly in elevation, and partly in section, the sand-supports being shown adjusted to have their lower headed ends conform to the outline of two patterns, and the cope, as a whole, being in readiness to have the sand packed therein about said patterns. Fig. 2 is a cross-sectional view through the cope, viewed in the opposite direction from Fig. 1, to show the opposite side of one of the bars, and with the patterns removed to show the manner in which the packed sand is held in the cope by the sand-supports; and Fig. 3 is a view showing the cope partly in section and partly in elevation, the view being on a line at right angles to that of Figs. 1 and 2.

Referring now to the drawing, 1 indicates the frame of the cope, 2 bars running from side to side of said cope and secured therein in any preferred manner in spaced parallel relation. Each of the bars 2 is preferably made of cast-iron and is constructed in a special manner to enable a series of sand-supports 3 to be adjustably held therein. Each of the sand-supports 3 comprises a cylindrical shank 4 having a pointed or tapering end 5 and a headed end 6. In practice, I employ ordinary wire nails for this purpose. Each of the bars 2 is provided on one side, as shown in the Figs. 1 and 3, with a longitudinally-extending recess 7, which terminates near the opposite ends of the bar, and which has an inclined wall 8, which incline extends from the bottom of the recess substantially to the top of the bar. The bottom of this recess is located at a distance of a half-inch, more or less, from the bottom, or the lower edge, of the bar, providing a laterally-projecting flange 9, extending throughout the length of said recess, or substantially so. A series of apertures 10 are bored through the flange 9 in a vertical direction, in such manner as to open into the recess 7, and with their inner edges lying in the line of the bottom of the wall 8 of said recess, as clearly shown by Fig. 3. The apertures 10 are equi-distant from each other, and extend substantially from end to end of the flange 9, and are for the purpose of receiving the sand-

supports 3, which have their pointed ends inserted therein from the bottom or lower side of the flange 9. As soon as the pointed end of each sand-support emerges from the upper end of its aperture 10, it will engage the wall 8 of the recess, as will be clearly seen; by forcing said sand-support further inward, its end will be deflected from a straight line, and the sand-support will thereby be clamped between the wall 8 and the wall of the aperture 10. Driving the nail further in will result in slightly bending it, but the incline of the wall 8 is preferably just enough to only slightly bend the nails, or sand-supports, even when they are driven to the limit of their inward adjustment. Various ranges of adjustment of these sand-supports, or nails, are shown in Fig. 1, to better illustrate which two patterns are shown inclosed in the cope. The purpose of having the inner edges of the apertures 10 lie in the line of the bottom of the incline 8 is to provide for the maximum outward adjustment of the nails; in other words, the binding of the nails begins as soon as their pointed ends emerge from the upper ends of the apertures 10. The pointed ends of the sand-supports, of course, facilitate the readiness with which the inner ends of said supports will pass over the inclined surface 8, as said supports are driven to their adjusted positions.

The manner of use of my improved bars, or the cope provided with such bars, will be readily apparent to those skilled in the art, and consists simply in inserting the nails in the various apertures and driving them in to the desired distance so that, as a whole, the nails will conform to the configuration of the pattern, or to several patterns, as the case may be. The nails, when driven into contact with the incline 8, are held firmly in position, and cannot be shaken or jarred loose. They can, however, be readily removed by a few taps of a hammer on their inner ends, or by the use of a hammer or nail-set, or similar implement. If one or more of the nails should not be positioned so as to lie within some weak portion of the body of sand, it may be bent to the desired position by blows from a hammer.

A further adjustment is secured by the preferred manner of mounting the bars in the cope, which is as follows: Cast integral with each bar, and projecting at right angles thereto on opposite sides and at each end of the bar, are lugs 11 having elongated apertures 12, through which, and through the sides of the cope, bolts 13 are passed for securing the bars in the cope. By loosening the nuts on these bolts the bars may be adjusted horizontally, as will be apparent, in order to bring the nails carried by the bars over the desired portion of the pattern. For the purpose of more securely holding, or

locking, the sand in place in the spaces between the various bars I provide each bar on its side opposite to that containing the recess 7, with a longitudinally-extending groove 14, which, in a well-understood manner, will assist in holding the sand from falling. Of course the bars 2 may be made of different lengths and different heights respectively, but with each set of bars secured in a cope, a wide range of adjustment of the sand-supports is provided, so that the same flask may be employed in connection with patterns which vary in size and configuration. Furthermore, the range of adjustment of the sand-supports is sufficient to accommodate within the cope as large patterns as can practically be accommodated in the same size of cope, specially constructed for the purpose. It will also be seen that a cope having my improved bars and sand-supports may be advantageously employed in any of the several systems of molding now in vogue. For instance, in a system where match-boards are employed and drawn from the cope, as well as in systems where the cope is placed on the packed drag, the upper half of the pattern secured in position on the half of the pattern in the drag, and the sand then packed in the cope about the pattern. I have not thought it necessary to describe in detail the operation of preparing the flask for receiving the molten metal, as such operation is well known.

The use of my improved cope, will, to a large extent, obviate the necessity of foundries, doing general foundry work, making a special cope for each particular pattern, and thus save the multiplication of flasks or copies, and consequently the time and money heretofore necessary to be expended thereon. The broad idea of my invention, that is to say, the bar for a molder's flask, having the series of sand-supports adjustably mounted therein will, as will be readily understood, include various other means of locking the sand-supports in position than the particular means shown and described herein, and, in a companion application filed August 15, 1907, Serial No. 388,589, I have shown and described constructions of bars differing from that of the present case, but coming within the broad idea of the invention.

I claim:

1. A molder's flask provided with a series of groups of sand-supports, the supports in each group being independently adjustable.
2. A molder's flask provided with a series of groups of sand-supports, the supports in each group being independently adjustable vertically.
3. A molder's flask provided with a series of rows of sand-supports, the supports in each row being independently adjustable.
4. A molder's flask provided with a series of rows of sand-supports, the supports in

each row being independently adjustable vertically.

5. A molder's flask provided with sand-supports adjustable vertically and horizontally.

6. A molder's flask provided with headed sand-supports adjustable vertically and horizontally.

7. A molder's flask provided with a series of groups of sand-supports, each of said supports being adjustable vertically and each group of sand-supports being adjustable in a body horizontally.

8. A molder's flask provided with a series of rows of sand-supports, the supports in each row being independently adjustable vertically, and each of said rows of supports being bodily adjustable horizontally.

9. A molder's flask provided with a series of supports, and a series of sand-anchors mounted in each support and adjustable vertically.

10. A molder's flask provided with a series of supports adjustable horizontally, and a series of sand-anchors mounted in each support and independently adjustable vertically.

11. A molder's flask provided with a series of supports, a series of sand-anchors mounted in each support and adjustable vertically, and means for locking said anchors in adjusted positions.

12. A molder's flask provided with a series of spaced parallel bars and a series of sand-supports mounted in each bar and vertically adjustable therein.

13. A molder's flask provided with a series of spaced parallel bars capable of horizontal adjustment, and a series of sand-supports mounted in each bar and vertically adjustable therein.

14. A bar for a molder's flask having a series of sand-supports adjustably mounted therein.

15. A bar for a molder's flask provided with a series of apertures and having an inclined surface cutting the plane of the axes of said apertures.

16. A bar for a molder's flask provided in one side with a longitudinally-extending recess having an inclined wall, and provided with a series of apertures extending from one edge of said bar through the body of metal afforded by said recess, and opening into the latter.

17. A bar for a molder's flask provided in one side with a longitudinally-extending recess having an inclined wall, and provided with apertures extending from one edge of said bar through the body of metal afforded by said recess and opening into the latter, the line of juncture of the wall of said recess with said body of metal being tangent to all of said apertures.

18. As a new article of manufacture a cast-iron bar for a molder's flask provided in

- one side with a longitudinally-extending recess having an inclined wall and provided with a line of apertures extending from one edge of said bar through the body of said metal afforded by said recess and opening into the latter, said inclined wall cutting the plane of the axes of said apertures, said bar being also provided on its opposite side with a locking groove.
- 10 19. A bar for a molder's flask provided with a series of apertures adapted to have nails, or the like, inserted therein to act as sand-supports, said bar having means associated with said apertures and adapted to be engaged by the nails inserted therein, to

cause the nails to be locked in adjusted positions.

20. A metal bar for a molder's flask provided along one edge with a series of apertures, said bar being configured to deflect 20 the ends of the nails, or the like, passed through said apertures.

In testimony whereof I have hereunto set my hand in presence of two subscribing witnesses.

DENNIS PARKS.
